UNITED STATES PATENT OFFICE.

JOHN TORAK, OF MOLINE, ILLINOIS.

DESIGN FOR A PLATE.

50,826.

Specification for Design.

Patented May 22, 1917.

Application filed March 24, 1917. Serial No. 157,277. Term of patent 7 years.

To all whom it may concern:

Be it known that I, JOHN TORAK, a subject of the Emperor of Austria, residing at Moline, in the county of Rock Island and State of Illinois, have invented a new, original, and ornamental Design for Plates, of which the following is a specification, reference being had to the accompanying drawing, forming part thereof.

The figure is a plan view of a plate showing my ornamental design.

I claim:

The ornamental design for a plate, as shown.

JOHN TORAK.
